Primary Examiner—Jeffrey Asch

(57) **CLAIM**

The ornamental design for a “communication system equipment enclosure,” as shown.

DESCRIPTION

FIG. 1 is a top, right and front isometric view of a communication system equipment enclosure;
FIG. 2 is a front elevational view thereof;
FIG. 3 is a rear elevational view thereof;
FIG. 4 is a left side view thereof;
FIG. 5 is a right side view thereof;
FIG. 6 is a top elevational view thereof; and,
FIG. 7 is a bottom elevational view thereof.
